UNITED STATES PATENT OFFICE.

JAMES JENKINS, OF BUCKLEY, WASIIINGTON.

DESIGN FOR A WATCH-CHARM.

SPECIFICATION forming part of Design No. 22,862, dated October 31, 1893.

Application filed April 7, 1893. Serial No. 469,472. Term of patent 7 years.

To all whom it may concern:

Be it known that I, JAMES JENKINS, of Buckley, in the county of Pierce and State of Washington, have invented a certain new and useful Design for Watch-Charms; and I do hereby declare the following to be a full, clear, and exact description of the invention, such as will enable others skilled in the art to which it appertains to make and use the same.

This invention relates to a design for watch charms which is clearly shown in the accompanying drawings, wherein—

Figure 1 is a perspective view of the charm attached to a chain. Fig. 2 is a similar view of the charm embodying and arranged to show the opposite side to that illustrated by Fig. 1.

Referring to the drawings, A designates a metallic block of elongated form having a flat

field or base C, which is smooth, and an opposite curved head which is united to the said base by a rectangular intermediate connection. The base extends laterally beyond the line of the head and the field or face thereof is provided with a rectangular inclosure D, which is less in dimension than the said base.

Having thus described the invention, what is claimed as new is—

A design for a watch charm as herein shown and described.

In testimony whereof I have signed this specification in the presence of two subscribing witnesses.

JAMES JENKINS.
